United States Patent Office.

CHARLES F. HERRICK, OF INDEPENDENCE, IOWA.

Letters Patent No. 105,075, dated July 5, 1870.

IMPROVEMENT IN REVERSIBLE LATCHES.

The Schedule referred to in these Letters Patent and making part of the same.

To all whom it may concern:

Be it known that I, CHARLES F. HERRICK, of Independence, in the county of Buchanan and State of Iowa, have invented certain new and useful Improvements in Latches; and I do hereby declare that the following is a full, clear, and exact description thereof, reference being had to the accompanying drawings and to the letters of reference marked thereon which form a part of this specification.

The nature of my invention consists in the employment of a reversible slotted plate, in combination with such other devices as will be hereinafter fully set forth.

In order to enable others skilled in the art to which my invention appertains to make and use the same, I will now proceed to describe its construction and operation, referring to the annexed drawings, in which—

Figure 1 is a front view,

Figure 2 is a transverse vertical section of my latch, and

Figure 3 is a plan of the reversible slotted plate as attached to the frame.

A represents the door-frame, and
B, the door.

On the frame A is secured a plate, C, which is provided with a curved slot, and has another plate, a, pivoted to it at its upper end.

On the outer side of the plate a is attached a cone-shaped button, D, which, with the plate a, is so constructed that, when hanging in its natural position, it will project a suitable distance beyond the edge of the door-frame.

The plate a is on its inner side provided with a hook, b, which projects inward through and below the

slot in the plate C, the edge of said plate extending up into said hook, as shown in fig. 2, which hook thus forms a guide or guard for the swinging button.

On the door B is secured a knob or button, E, with plate G extending flush with the edge of the door.

In closing the door, the edge of the same strikes the side of the cone-shaped pendulum D a, moving the same out of the way, and, when the door is closed, said pendulum resumes its perpendicular position, extending over a portion of the plate G, and thus holding the door closed.

The slot in the plate C is made in such a manner that either end of the plate may be turned up, thereby adapting the latch to both right and left-hand doors without the necessity of turning the plate over, thus always having the finished side of the plate out.

Having thus fully described my invention,

What I claim as new, and desire to secure by Letters Patent, is—

1. The reversible slotted plate C, in combination with the cone-shaped pendulum D a, provided on its inner side with the hook b, substantially as and for the purpose herein set forth.

2. The reversible slotted plate C, cone-shaped pendulum D a, provided on its inner side with hook b, in combination with plate G and button or knob E, all constructed and arranged substantially as herein set forth.

In testimony that I claim the foregoing as my own, I affix my signature in presence of two witnesses.

C. F. HERRICK.
